US0D1067213S

(12) **United States Design Patent** (10) Patent No.: **US D1,067,213 S**
(45) Date of Patent: ** Mar. 18, 2025

(54) **LOUDSPEAKER**

(71) Applicant: **Hui He**, Guangdong (CN)

(72) Inventor: **Hui He**, Guangdong (CN)

(**) Term: **15 Years**

(21) Appl. No.: **29/981,843**

(22) Filed: **Jan. 2, 2025**

(51) LOC (15) Cl. **14-01**

(52) U.S. Cl.

USPC **D14/216**

(58) **Field of Classification Search**

USPC D14/216, 210, 215, 207, 204, 211, 212
CPC H04R 1/02; H04R 1/025; H04R 1/026;
H04R 1/323

Primary Examiner — Jack Reickel

Assistant Examiner — Russell Carnell Smith, Jr.

(57) **CLAIM**

The ornamental design for a loudspeaker, as shown and described.

DESCRIPTION

FIG. 1 is a front, top and right-side perspective view of the loudspeaker showing my new design;
FIG. 2 is a front elevation view thereof;
FIG. 3 is a rear elevation view thereof;
FIG. 4 is an enlarged left side elevation view thereof;
FIG. 5 is an enlarged right side elevation view thereof;
FIG. 6 is a top plan view thereof;
FIG. 7 is a bottom plan view thereof;
FIG. 8 is a rear, bottom and left-side perspective view thereof; and,
FIG. 9 is an alternate configuration in another perspective view thereof.
The broken lines throughout the drawing figures depict portions of the loudspeaker that form no part of the claimed design.

1 Claim, 9 Drawing Sheets
